UNITED STATES PATENT OFFICE

2,055,346

HIGH VOLTAGE ELECTRICAL APPARATUS

Levin W. Foster, Pittsfield, Mass., assignor to
General Electric Company, a corporation of
New York

Application April 30, 1935, Serial No. 19,001

7 Claims. (Cl. 175—360)

My invention relates to high voltage electrical apparatus, more particularly to high voltage liquid-immersed apparatus such as transformers and reactors. Such apparatus is usually enclosed 5 in a metal casing containing a suitable insulating liquid and the high voltage terminals of the apparatus are brought out of the casing through suitable insulating bushings. These bushings are expensive and one of the objects of the invention 10 is to provide an arrangement which does not require their use. Unless the capacity of the apparatus is very small, its temperature may become excessive during operation unless there is some efficient way of cooling it. Another object 15 of the invention is therefore to provide an improved arrangement for carrying away and dissipating the heat generated in the apparatus during its operation.

Further objects and advantages will be apparent from the following description taken in connection with the accompanying drawing in which Fig. 1 is a view in elevation of a high voltage transformer and means for cooling it, the transformer and its cooling means being arranged in accordance with the invention; Fig. 2 is a plan view of the transformer and its cooling means shown in Fig. 1; and Fig. 3 shows diagrammatically the arrangement of the windings in the transformer.

Like reference characters indicate similar parts of different figures in the drawing.

The transformer 10 shown in Fig. 1 includes a series of individual units, each having three windings 11, 12, and 13. The windings 11 are all connected in series between a high voltage terminal 14 and a ground connection 15. The windings 12 and 13 are connected to form coupling circuits between the windings 11 to assure a uniform distribution of voltage throughout the units. The winding 13 of the unit next to the ground connection 15 is provided with terminals 16 for connection to an external low voltage circuit. Each transformer unit is surrounded by a cylindrical wall of insulating material such as porcelain, 45 these walls being secured together to form a common insulating casing 17 for the transformer 10. The transformer 10 with its casing 17 is mounted on a hollow metal base 18 which may also support some insulating bushings 19 for the low voltage terminals 16. The cover 20 of the casing 17 is insulated from ground by the casing so that it need not be insulated from the high voltage terminal 14 and this terminal 14 may therefore be in the form of a simple terminal post.

The transformer 10 is immersed in an insulat-

ing liquid 21 which fills the casing 17 and extends through a pipe 22 to a conservator 23 provided with a breather 24 to permit expansion and contraction of the liquid in the temperature changes. The pipe 22, which with the conservator 23 and its breather 24 is supported on the cover 20, is connected to and communicates with the header at one end of a horizontally disposed metal heat radiator 25. The header at the other end of the radiator 25 communicates through and is supported by a pipe 26 which is in turn supported by a vertical hollow post 27 spaced from the casing 17 and mounted on the hollow base 18 with which it communicates also. The liquid 21 not only fills the casing 17 but also extends and may circulate 10 through the radiator 25, the hollow insulating post 27 and the hollow base 18, back into the lower end of the casing 17. No insulation is necessary 15 between the high voltage terminal 14 and the radiator 25 and conservator 23 because the radiator and conservator are effectively insulated, as well as supported, by the casing 17 and the hollow post 27.

The high voltage terminal 14 is connected by a conductor 28 and a protective device, such as a 25 fuse 29, to a terminal 30 arranged for connection to an external high voltage circuit. The hollow post 27 is shown as being formed in sections connected together by liquid-tight joints and the fuse 29 is mounted between a support 31 at the 30 top of the post 27 and the joint between the upper two sections of the post.

While the transformer 10 is in operation, it generates heat which must be dissipated to avoid excessive temperature of the transformer. This 35 heat is absorbed by the liquid 21 surrounding the transformer, the heated liquid then rising by convection into the radiator 25 where it is cooled, the cooled liquid then descending through the hollow post 27 and then flowing through the hollow base 40 18 back into the casing 17, ready to absorb more heat. In the arrangement which has been described, the radiator 25 extends laterally in a more or less horizontal position from the upper part of the casing 17, as shown in Fig. 1, so that 45 it is well exposed to the surrounding air to which it may dissipate heat very effectively. Some additional heat may also be dissipated of course through the walls of the post 27 and the metal base 18.

The invention provides an inexpensive and reliable arrangement and is particularly useful where it is desired to obtain a small amount of low voltage power from a high voltage circuit. The invention has been explained by describing and 55

illustrating a particular arrangement and application thereof but it will be apparent that changes may be made without departing from the spirit of the invention and the scope of the 5 appended claims.

What I claim as new and desire to secure by Letters Patent of the United States, is:

1. The combination with electrical apparatus of an insulating casing therefor, a metal heat 10 radiator supported at one end by said casing and communicating therewith, a hollow insulating post spaced from said casing and supporting and communicating with the other end of said radiator, means providing communication between the 15 lower ends of said casing and post, and an insulating liquid in said casing, radiator and post.
2. The combination with electrical apparatus of an insulating casing therefor, a hollow insulating support spaced from said casing, a metal 20 heat radiator supported by the upper ends of said casing and support, means providing communication between the lower ends of said casing and support, and an insulating liquid in said casing, radiator and support.
- 25 3. The combination with electrical apparatus of an insulating casing therefor, a hollow base supporting and communicating with said casing, a hollow insulating support spaced from said casing and mounted on and communicating with said base, a metal heat radiator supported by and providing communication between the upper ends 30 of said casing and support, and an insulating liquid in said casing, radiator, support and base.
4. The combination with electrical apparatus 35 of an insulating casing, a hollow insulating support spaced from said casing, means providing communication between the lower ends of said

casing and support, a metal heat radiator supported substantially horizontally by and communicating with the upper ends of said casing and support, and an insulating liquid in said casing, radiator and support.

5. The combination with electrical apparatus of an insulating casing therefor, a high voltage terminal for said apparatus on the upper end of said casing, a hollow insulating support spaced from said casing, a metal heat radiator supported by and providing connection between the upper ends of said casing and support, means providing communication between the lower ends of said casing and support, a protective device and a terminal mounted on said support and connected to 15 said high voltage terminal, and an insulating liquid in said casing, radiator and support.

6. The combination with electrical apparatus of an insulating casing therefor, a metal heat radiator extending laterally from the upper part 20 of said casing and communicating therewith, the end of said radiator adjacent the casing being supported thereby, an insulating support for the other end of the radiator, and an insulating liquid in said casing and radiator.

7. The combination with electrical apparatus of an insulating casing therefor, a metal heat radiator extending laterally from the upper part 30 of said casing and supported at one end thereby, said radiator communicating with the upper part of said casing, insulating means supporting the other end of said radiator providing communication between said radiator and the lower part of said casing, and an insulating liquid in said 35 casing and radiator.

LEVIN W. FOSTER.
